RADIATOR CORE MOUNTING

Fred M. Young, Racine, Wis., assignor to Young
Radiator Company, Racine, Wis.

Application September 12, 1947, Serial No. 773,612

6 Claims. (Cl. 257—125)

1

The principal objects of the present invention are to provide a cradle within which to secure together suitably designed headers of a radiator and form a unit structure with maximum strength and longevity, particularly where the device is subjected to vibrations, such as when mounted on a tractor, truck, engine support and the like.

Other objects of my invention are to provide a unit structure having means for securing it to the supporting frame in a manner whereby the unit will be firmly held to the supporting frame, and without imparting harmful strains to the radiator tanks and the core, whereby the connections are made between the cradle and supporting frame by means of detachable bolts which bind the cradle firmly to the frame.

Generally stated objects of the present invention are to provide a U-shaped cradle structure with means whereby the headers of the radiator are firmly held in the cradle in a manner which will protect the radiator headers and core against injury from vibrations and strains.

To these and other useful ends my invention consists of parts, combinations of parts or their equivalents and mode of assembly as described and claimed and shown in the accompanying drawings in which:

Fig. 1 is a front elevational view of my improved radiator unit illustrating the holding bolts after being inserted in the opening in the cradle.

Fig. 2 is a side elevational view of the unit as shown in Figure 1 less the holding bolts.

Fig. 3 is a bottom view of the unit shown in Figure 1.

Fig. 4 is a sectional view taken on line 4—4 of Figure 1.

Fig. 5 is a sectional view taken on line 5—5 of Figure 2 showing the right hand lower corner of the unit.

Fig. 6 is an enlarged sectional view of the outlet fitting shown in Figures 1, 2 and 3.

Fig. 7 is a fractional section of the inlet connection to the upper header illustrating the manner of securing it to the header, and Figure 8 is a rear view of the lower header outlet.

As thus illustrated the upper header is designated by reference character A and the lower header is designated by reference character B. The cradle in its entirety is designated by reference character C and the radiator core is designated by reference character D.

Core D of my device comprises preferably three rows of flattened tubes 10 with the wide sides of the tubes arranged transverse of the core as

shown in Figures 4 and 5, the tubes extending through a multiplicity of closely spaced fins 11. The headers have somewhat similar tube plates 12 and 12' with flanges 9 through which the ends 5 of tubes 10 extend, and are bonded thereto as illustrated in Figures 4 and 5.

Header A is shaped about as shown in Figures 1 and 2 with spaced inwardly projecting embossments 13 so as to add strength to the header, 10 the ends of this header being tapered as at 14 and the header being provided with a projection 15, having a closure cap 16. An over flow tube 17 is secured to member 15 as indicated in Figure 2, this over flow being bent downwardly as illustrated in Figure 2, the end terminating preferably as at 18 and being connected to a long drain pipe 19 shaped about as shown by dotted lines in Figure 1, the upper end being connected to tube 17 preferably by a synthetic sleeve 20.

20 Tube 17 preferably extends through header A (see Figure 2). Tube 19 because of its shape and manner of connection to tube 17, may be made of low priced material such as steel or the like, and is clearly replaceable if injured. Tube 19 is 25 secured to the side plates of the cradle as will hereinafter appear.

Upper header A and its tube plate 12 is considerably wider than tank B and is provided with an inlet member 25, the lower end being circular in 30 cross section and adapted for convenient connection to a rubber hose which is connected to the engine jacket. The rear side 26 of header A is flat, and the upper edge of this header is depressed somewhat as at 27 and having secured 35 thereto a bracket 28 for holding the engine hood into position. The forward end of member 25 is secured to the header as follows (see Figure 7):

It will be noted that the part that extends into the header is considerably narrower than the 40 rear end of this member; therefore the part that fits into the header is necessarily considerably wider than its depth. This part is therefore oblong in shape (not shown), the opening being flanged as at 29 and is adapted to fit snugly 45 around the inlet 25 at this point and being bonded thereto. The inner end of inlet 25 at its top extends upwardly and rearwardly as at 30 and is adapted to lie under member 27 as illustrated and is preferably bonded and riveted to this member at the point of contact. The forward end of member 25 is cut away at an angle as at 32 making it possible to insert the forward end of member 25 into flange 29, after which member 30 may be bonded and riveted to the header.

It will be seen that member 25 will be firmly

held to the header by member 30 and flange 29, whereas without member 30 member 25 would not be stable enough for the purpose.

It will be seen that I have provided an upper header having an inlet with adequate capacity and strength and a novel over flow pipe.

On the forward side of headers A and B I provide a buffing or rubbing strake 33 having a length and shape about as shown in Figures 1 and 2 and being spot welded or riveted to the header plate and preferably bonded to this plate. This strake is provided to prevent contact of the header with fitting members or accessories which might result in injury to the thin delicate material of the header.

Lower header B is provided with a header plate 12' having flanges 9 through which the lower ends of tubes 10 extend and to which the tubes are bonded.

I will now describe the shape of header plates 12 and 12' and the manner of attaching these plates to the header tanks. The perimeters of headers 12 and 12' are shaped as shown in Figures 4 and 5 wherein flanges 42 are connected to plates 12 and 12' by means of projections 43 which form wells into which flanges 44 of the header tanks extend, the side and end walls of each header tank being extended outwardly as at 45. Thus it will be seen that when the tank is properly positioned as illustrated, there will be an accumulation of bonding material 46-46 forming a triple bond between the header plates and header tanks. In so far as the header plates are concerned, they are somewhat similar and therefore it is not thought necessary to illustrate in detail an upper header. Header B is substantially flat on its bottom but having on opposite ends thereof inwardly projecting embossments 47 and 48 for a purpose which will hereinafter appear.

I will now describe my improved cradle and how the headers are secured thereto for the purpose as outlined in the preamble of this specification.

U-shaped end members 55 have at their tops a shape about as shown in Figure 1. The body of members 55 at their tops are offset as at 56, and the base of the channel being extended upwardly and inwardly as at 57 so as to fit snugly against surface 14, the portion 58 lying flat on surfaces 14 and having openings 59. For convenience in bonding these members to the header, members 58 are provided with hooks 60 for a purpose which will hereinafter appear.

The upper ends 35-35 of the front flanges of members 55 are widened and separated from members 57 by a cut away portion as at 36-36, their ends lying on the front of the tank of member A, and shaped so as not to contact flange 42 of the header plate. Member 57 also does not contact this flange of the header plate.

An end portion of the upper end of the rear flange of members 55 is cut away so as to clear the header. To take the place of this cut away portion, I provide plates 61 which are shaped about as shown in Figure 2, their forward edges being welded to members 55 as at 62. The upper edges of members 61 lie on the ends of the rear portion of headers A and have soldering holes 63 so these members may be firmly bonded to member A. These members do not contact flanges 42 of the tube plates.

The bases of members 55 terminate at their bottoms as at 64. These members are offset inwardly slightly as at 65. I provide a heavy

U-shaped bracket 66, the ends of which lie under the ends of the base of members 55 and are riveted thereto as at 67, the base lying against the bottom of header B. The lower ends of the flanges of members 55 are shaped as shown in Figures 1, 3 and 4. These members are offset inwardly slightly as at 69 having downwardly extending portions 70-70 which lie on the sides of tank B, each having solder holes 68 to facilitate the bonding operation. The lower ends of members 70 are folded under member 66 as at 71, (see Figures 2 and 3) and being spot welded or riveted to member 66 and bonded thereto if thought desirable.

Member 66 has openings 75 which are large enough to freely receive the heads of bolts 76, these bolts being carriage bolt type with square shanks 77. Openings 75 are on their inner sides provided with cut away portions 78 forming keys for the reception of shanks 77. Embossments 47 and 48 are made large enough to clear the heads of bolts 76 when they are inserted into openings 75 and moved to the position shown in Figure 3 so there is never a contact between these heads and the bottom of the tank.

It will be noted that the flanges of channels C are further apart than the width of header B and that these flanges are therefore offset inwardly as at 69. It will also be noted that the upturned ends of bracket 66 are spaced a short distance from the ends of the lower header B, therefore slight variation in expansion and contraction between members D and C will be permitted.

It will be seen that when the bolts are in the position shown in Figures 1 and 3, openings in the frame support may be made to register with the bolts so the assembly may be conveniently and firmly secured to the frame.

The cradle member, it will be seen is U-shaped and the free ends of members 55 may be spread apart far enough for the free reception of headers A and B after which members 55 will assume the position shown in Figure 1.

Before any soldering is done to the headers an adjustable pulling tool or jig is positioned under hooks 60, the pulling tool then being shortened by screws or otherwise so as to force the radiator assembly downward and surfaces 58 snugly against surfaces 14, after which members 35, 58, 61 and 70 are bonded to the tanks of headers A and B. Thus the radiator assembly will be snugly held within member C, member A forming one end of the frame and there will be provided as described, a firm bonding between the flanges of members 55 and the headers and a firm fastening between members 71 and member 66 and that when bolts 76 are made taut members 66 and 71 will be firmly held on the supporting frame of the unit.

Under some circumstances it may be desirable to prevent metal to metal contact between the bottom of header B and member 66. When this is thought desirable a thin sheet of yielding material 79 is provided to accomplish this result (see Figures 4 and 5).

I will now describe the outlet element of member B.

Member B is cut away in its rear lower corner between points 85 and 86 (see Figure 6) thus providing an elongated L-shaped opening in the header tank. An element 87 is flanged as at 88 and 89. Flange 88 is adapted to surround three sides of the cut away portion in the tank and be bonded thereto. An element 90 is circular in cross section at its rear end and having a flange 91.

which registers with flange 89 and with the rear surface of the tank which surrounds three sides of the cut away portion on the rear of the tank and being bonded to these parts.

Thus it will be seen that an elongated opening in the tank is provided having area about equal to the area of member 90 so as to form a free outlet for the cooling liquid and a reinforced connection between member 90 and the tank.

It will be seen that the flanges of members 55 shield the corners of the fins. In order to make full use of the corners of the core I provide openings 92 in the flanges thus to provide free air passageways through the corners of the core so as to provide maximum heat exchange capacity for the core.

It will be seen by scrutinizing the various figures that applicant has provided a unit which conforms to the preamble of this specification; that the unit is easily manufactured at low cost and neat in appearance and efficient and well protected for storage and shipping purposes.

It will be understood that applicant does not wish to be limited to the specific design disclosed; that many minor detail changes can be made without departing from the spirit and scope of my invention as recited in the appended claims.

Having thus shown and described my invention, I claim:

1. A device of the character described comprising, upper and lower headers and a number of tubes forming operating connections therebetween, forming a radiator, a cradle comprising in combination, generally channel shaped side frame members with their flanges turned inward, the upper ends of the flanges of the channels being widened, the front flanges at their ends being bonded to the front of the upper header and the rear flange being extended rearward and bonded to the ends of the header, the upper ends of the base of said channels being bonded to the ends of the header and the bottom ends of the base of the channels terminating adjacent the top of the bottom header and a short distance longitudinally therefrom, the flanges of said channels at their bottom ends being widened and extended a distance below their bases and being offset inwardly and adapted to lie on the front and rear of the bottom header directly below said offsets and being bonded to the header, a U-shaped metal strip having its ends secured to the lower ends of the base of said channels, its base lying against the bottom surface of the lower header, spaced apart openings in the base of said U-shaped metal strip having keys extending longitudinally, inwardly extending embossments on the bottom of the lower header adapted to receive the heads of bolts, when the bolt heads are inserted through said openings and the bolt moved into said keys, the bottom ends of said channel flanges being folded inwardly under the base of said U-shaped metal strip and being secured thereto, the ends of said upper header converging inwardly forming a seat for the upper end of the base of said channel frame members, the upper end of the base of said channel frame members having means whereby they may be jig contacted and urged toward each other for firmly seating the radiator into the cradle, before bonding the headers to the flanges and the upper header to the base of the channels.

2. A device as recited in claim 1 including, the upturned ends of said U-shaped bracket being positioned a short distance from the ends of the lower header to thereby cooperate with said flange offsets to provide slightly vertical yielding means between headers.

3. A device as recited in claim 1 including, the bottom ends of said channel flanges being folded inwardly under said U-shaped metal strip, to thereby form a support for said cradle.

4. A device as recited in claim 1 including,

said upper header being considerably wider than the lower header and having on its upper surface and at the forward side thereof a filler extension having a closure cap, an overflow tube secured to the rear side of said filler extension and being bent downwardly and extending through the upper header adjacent the rear side of the core of said radiator and terminating a short distance below the bottom of the header.

5. A device as recited in claim 1 including, air flow openings in the widened portion of said flanges and positioned to thereby permit air to flow through the part of the radiator core covered by the flanges.

6. A device of the character described comprising, upper and lower headers and a number of tubes forming operating connections therebetween, forming a radiator, a cradle comprising in combination, generally channel shaped side frame members with their flanges turned inward, the upper ends of the flanges of the channels being widened, the front flanges at their ends being bonded to the front of the upper header and the rear flange being extended rearward and bonded to the ends of the upper header, the upper ends of the base of said channels being bonded to the ends of the header and the bottom ends of the base of the channels terminating adjacent the top of the bottom header and a short distance longitudinally therefrom, the flanges of said channels at their bottom ends being widened and extended a distance below their bases and being offset inwardly and adapted to lie on the front and rear surfaces of the bottom header directly below said offsets and being bonded to the header, a U-shaped metal strip having its ends secured to the lower ends of the base of said channels, its base lying against the bottom surface of the lower header, spaced apart openings in the base of said U-shaped metal strip having keys extending longitudinally, inwardly extending embossments on the bottom of the lower header adapted to receive the heads of bolts, when the bolt heads are inserted through said openings and the bolt moved into said keys, the bottom ends of said channel flanges being folded inwardly under the base of said U-shaped metal strip and being secured thereto, the ends of said upper header converging inwardly forming a seat for the upper end of the base of said channel frame members, the upper end of the base of said channel frame members having means whereby they may be jig contacted and urged toward each other for firmly seating the radiator into the cradle, before bonding the headers to the flanges and the upper header to the base of the channels.
